SAMUEL I. BERGER, OF NEWARK, NEW JERSEY

MECHANICAL FIGURE WHEELED TOY

Application filed February 24, 1927. Serial No. 170,452.

The present invention is concerned with improvements in spring motor driven toys of the class in which the impelling motor serves in a dual capacity to impart movement to a carriage and to actuate one or more toy figures borne by the carriage.

More specifically, the toy is preferably in the nature of a vehicle driven alternately forwardly and rearwardly and in directions more or less chance determined by one or more freely turning steering wheels. Preferably, the movements of the toy figure are synchronized with the movements of the vehicle and so correlated therewith as to produce a grotesque figure action which seems to be rather naturally caused by or associated with the somewhat jerky backward and forward motion of the vehicle.

Objects of the invention are to provide improved mechanism for causing and controlling the movements of the vehicle and figure, improved means for mounting the figure, novel features of figure construction and unique connections between the motor and the parts which it drives.

More general objects are to provide a toy which will be grotesque and intriguing both in appearance and operation, and a toy of simple, practical construction which will be rugged and durable in use and yet well suited to the requirements of economical manufacture.

The invention may be more fully understood from the following description taken in connection with the accompanying drawings, wherein:

Figure 1 is a view in side elevation of my improved toy.

Figure 2 is a longitudinal sectional view therethrough.

Figure 3 is a fragmentary bottom plan view thereof.

Figure 4 is a view similar to Figure 1, of a modification.

Figure 5 is a fragmentary rear elevation of the embodiment of Figure 4.

Figure 6 is a fragmentary view of the ladder device, and

Figure 7 is a fragmentary view of the ladder mounting clip.

Referring first to the form of the invention shown in Figures 1 to 3 of the drawings, a toy automobile includes a platform portion 10 upon which may be mounted a hood portion 11, windshield portion 12, mudguards 13 and steps 14. All of these parts are preferably stamped from tin and connected together in a manner well known in the art by the usual bendable tongues 15 on certain parts working through associated slots in adjacent parts.

The representation of a steering post 16 and steering wheel 17 are preferably employed, the post passing through the lower or dashboard forming section 12^a of the windshield section 12 and through the platform 10. The sides of the windshield section are turned rearwardly to define uprights 12^b.

A conventional mounting may be used for the freely turning front traction wheels 18. The front wheel axle 18^a may rotate in aligned ears 19 integral with a yoke like bracket 20 including aligned apertured horizontal arms 21 which rotate freely on a vertically disposed headed rod 22 passed through openings in the hood 11 and platform 10. The platform is formed with a rounded depression 23 encircling the rod opening and contacting with the upper arm 21 to minimize friction between the bracket 20 and the platform 10.

Secured under the rear of the platform 10 is a motor frame including a horizontal plate 24 and upwardly extending end pieces 25, 26 carrying tongues 27 which extend through the platform 10 and are bent over into engagement therewith. The rear traction wheels 28 are fixed to an axle 29 turning in ears 30 struck downwardly from the plate 24.

24. The axle is turned alternately in opposite directions to reverse the direction of movement of the vehicle by a segmental or mutilated crown gear 31 acting alternately on a pair of spaced pinions 32 carried by the axle.

One end of a convolute motor spring 33 is anchored to the piece 25 and its other end to a driving shaft 34 in vertically aligned openings in the platform 10 and plate 24 and retained against axial movement by out-struck pins or burrs 35. A driven counter-shaft 36 also turning in the platform and plate, carries a pinion 37 driven by a gear 38 on shaft 34. Shaft 36 carries the segmental gear 31.

The upper end of shaft 36 projects well above the platform 10 passing through a hollow figure body 39 and bearing the movable head 40 of the figure.

Preferably a curved metallic plate 41 secured upon the rear end of the platform 10 simulates the sides and back of a seat. The figure body 39 is arranged within the confines of the plate 41. This body may be of general cylindrical form bent from a single sheet of metal and having the abutting sheet edges tongued as at 42 to pass through and engage with the intermediate rear portion of the plate 41. The body is legless and an inclined plate 43 simulating a lap robe is connected at its lower forward edge to the platform 10 by tongues 44 and at its upper rear edge to the body 39 by tongues 45. The upper end of the body is crimped inwardly to define a shoulder portion 39a within which the head 40 rotates and which conceals the lower end of the head.

A single U shaped piece of metal has its intermediate portion 46 extending transversely through the body 39 just below shoulders 39a, being received in slots 47 at opposite sides of the body, its arms 48 extending forward to simulate the arms of the figure the free ends or hand portions of which are engaged with the steering wheel 17 in any suitable manner.

Head 40 is formed of a pair of cooperating hollow sections having overlying tongues 49 at their edges. The shaft 36 projects through the top of one head section and through the bottom of the opposite one whereby the two sections are connected each to the other and independently to the shaft 36, as best shown in Fig. 2.

It is to be understood that all of the various parts of the toy may be suitably ornamented to simulate the various parts of the car and figure which they represent. The motor is wound by turning a key 50 integral with the shaft 34 while manually holding the wheels 28 against turning movement.

In operation, the vehicle is propelled alternately ahead and astern by the action of the segmental gear 31 on the rear axle pinions 32.

The direction of movement in either a forward or reverse direction is chance determined by the freely swinging front steering wheel set, these wheels being influenced by all slight imperfections in the surface over which they run as well as by the jolts incidental to each reversal of direction of movement of the toy. These reversals will be quite jerky and abrupt since each time gear 31 passes from engagement with one pinion 32 and into engagement with the other it will be opposed by the full momentum of the travelling vehicle.

Between each reversal of the vehicle the head 40 will be swung through 180°, the figure thus appearing to be turning his head in order to observe the ground over which he is steering. Obviously the action is both grotesque and fascinating to watch, due to the irregular movements of the toy and the sudden changes in its direction of travel.

I have shown a hollow toy dog 51 secured on the step 14 by tongues 52, passed therethrough and a toy suitcase 53 apparently resting on the forward mudguard 13 but in reality held by its slot and tongue engagement at 54, 55 with step 14 and upright 12 respectively.

In Figures 4 to 7 I have illustrated a modification of the invention, which is generally similar to the toy above described except for minor changes in the vehicle design and the provision of a different type of movable figure and a novel supporting mechanism therefor which causes it to have an eccentric motion.

Here the vehicle 60 is of substantially the same construction described above except that a seat 61 is arranged well forwardly on the platform and the stationary representation of a driver 62 is arranged on the seat as well as a toy dog 63. The wheels and driving means are similar to those above described. The upper end of a driven shaft 64 corresponding to shaft 36 projects for a short distance above the platform behind the seat 61, and carries a support designated generally by the reference numeral 65.

This support, preferably bent from a single piece of metal, includes a plate 66 disposed at an angle to the axis of shaft 64 and having aligned apertured brackets 67 projecting laterally from its upper and lower edges and receiving the shaft. The side edges of the plate are rolled over to define substantially three-quarter cylindrical inclined socket portions 68 removably receiving the lower ends of the uprights 69 of a ladder including rungs 70. A hollow figure 71 on the ladder is formed of a pair of similar sections joined together by overlapping tongues 72. The figure may be held in position on the ladder by tongues 73, 73 integral with certain of the rungs 70 and entering slots in the body and feet portion of the figure.

In operation the upper end of the ladder will swing in a circular path its movements being intermittent as the vehicle stops and starts. The movement is really a positive one since the support 65 is fixed to the shaft 64. In appearance, however, the ladder and the figure which it bears will appear to be swung about willy-nilly by the sudden stopping and starting of the car.

It will thus be seen that there is herein described a device in which the several features of this invention are embodied, and which device is its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. A toy automobile including a platform mounted on wheels, a curved plate supported on edge of the platform and simulating the sides and back of a driver's seat, a hollow generally cylindrical figure arranged within the plate and comprising a single curved sheet of metal having its edges arranged in juxtaposition, and slot and tongue connections between said edges and the intermediate portion of the plate.

2. A toy automobile including a platform mounted on wheels, a curved plate supported on edge of the platform and simulating the sides and back of a driver's seat, a hollow generally cylindrical figure arranged within the plate and comprising a single curved sheet of metal having its edges arranged in juxtaposition, and slot and tongue connections between said edges and the intermediate portion of the plate, the upper end of the body being crimped inwardly to define sloping shoulder portions, and a rotatable head, the lower end of which is concealed by the shoulders.

3. A toy automobile including a platform mounted on wheels, a curved plate supported on edge on the platform and simulating the sides and back of a driver's seat, a hollow generally cylindrical figure arranged within the plate and comprising a single curved sheet of metal having its edges arranged in juxtaposition, and slot and tongue connections between said edges and the intermediate portion of the plate, an inclined laprobe portion concealing the lower end of the legless body, said laprobe portion comprising an inclined sheet of metal connected at its lower

forward edge to the platform and at its upper rear edge to the body.

4. A toy automobile including a wheeled carriage, a mudguard and step forming strip integral with the body, a dashboard portion secured to the body and including a rearwardly turned lateral flange, and a toy article apparently resting on the mudguard and having slot and tongue connections with the flange and step.

Signed at Newark in the county of Essex and State of New Jersey, this 23rd day of February A. D. 1927.
